P. B. OLSON.
AUTOMATIC TEMPO REGULATOR.
APPLICATION FILED AUG. 31, 1912.

Patented Oct. 28, 1913.

UNITED STATES PATENT OFFICE.

PAUL B. OLSON, OF CHICAGO, ILLINOIS.

AUTOMATIC TEMPO-REGULATOR.

1,076,695.

Specification of Letters Patent. Patented Oct. 28, 1913.

Application filed August 31, 1912. Serial No. 718,021.

To all whom it may concern:

Be it known that I, PAUL B. OLSON, a resident of Chicago, in the county of Cook and State of Illinois, have invented certain new and useful Improvements in Automatic Tempo-Regulators, of which the following is a specification.

My invention relates to automatic tempo regulator mechanism, an arrangement to be used in connection with pneumatically operated instruments to automatically control the speed of travel of the music sheet over the tracker board to thereby control the tempo.

One of the important objects of the invention is to provide improved piston mechanism for controlling the throttle valve of the motor which propels the music sheet and to cause positive actuation of the piston mechanism by means of compressed air.

Another object is to provide improved valve mechanism whose operation is controlled by the passage of the music sheet over the tracker board and which in turn controls the flow of compressed air to either side of the throttle valve.

These and other objects and features of the invention are adapted to be carried out by the mechanism shown in the accompanying drawing, the drawing showing more or less diagrammatically the valve construction and arrangement and coöperation thereof with reference to the tracker board and the music sheet driving motor.

Referring to the drawing, I have shown a tracker board 1 over which passes the music sheet 2 propelled by a roller 3 connected in suitable driving relation with the pneumatic motor 4. This motor is in practice connected with a source of suction as for example bellows, and the suction effect on the motor is controlled by suitable throttle valve mechanism. The throttle valve mechanism shown on the drawing comprises a chest connected at its upper and lower ends through ducts 7 and 8 with the motor and suction source respectively. An intermediate wall 9 forms the valve seat and has the passageway 10, a valve 11 co-operating with the passageway to control the flow of air from the motor toward the suction source, or in other words to control the speed of the motor.

Describing now the mechanism for automatically adjusting the valve 11 to thereby automatically adjust the speed of the motor

and travel of the music sheet, the valve stem 12 of valve 11 is connected with a piston 13 reciprocable in cylinder 14. Seated on top of this cylinder is a valve block 15 having adjacent its ends the exhaust outlets 17 and 18 for coöperating with exhaust ports 19 and 20 through the upper wall of the cylinder. Extending from the ends of the valve block 15 are rods 21 and 22 terminating in pistons 23 and 24 respectively, these pistons operating in the auxiliary cylinders 25 and 26 supported from the end walls of cylinder 14. Auxiliary cylinder 25 communicates through duct 27 with the left end 70 of cylinder 14 and auxiliary cylinder 26 communicates through duct 28 with the right end of cylinder 14, the connection of each duct with the respective auxiliary cylinder being such that the piston within the auxiliary cylinder travels to either side of such connection. With this arrangement, pressure applied in either auxiliary cylinder at the outside of the piston therein will cause first shifting of the valve block 15, 80 and then exposure of the corresponding connection so that pressure will be transmitted to cylinder 14 and the piston therein moved, the movement of the valve block having opened the exhaust outlets in advance of 85 the piston 13 and closed the opposite exhaust outlets.

For automatically controlling the application of pressure to the auxiliary cylinders in accordance with the tempo desired, valve mechanism is associated with the tracker board. A chest 29 has connection through conductor 30 with a suitable pressure-source such as a motor or bellows, the ends of the chest being connected through conductors 95 31 and 32 with the outer ends of auxiliary cylinders 25 and 26 respectively. Partitions 33 and 34 within this chest form seats for valves 35 and 36, these valves coöperating with ports 37 and 38 respectively to control 100 the supply of pressure to the auxiliary cylinders. Above the chest 29 is the structure 39 for supporting pneumatic mechanism for controlling the valves 35 and 36. Two pockets 40 and 41 are provided over which diaphragms 42 and 43 are applied and connected at their centers with the stems 44 and 45 extending upwardly from the valves 35 and 36 respectively. Compression springs 47 and 48 in pockets 40 and 41 tend to expand the 105 respective diaphragms out of the pockets. These pockets are, however, connected

through conductor 49 with a suction source so that if the pockets 40 and 41 are otherwise closed the diaphragms will be drawn into the pockets by the suction effect so that 5 the valves 35 and 36 are held up to prevent flow of pressure to the auxiliary cylinders. As soon as either pocket is opened to atmosphere, the suction effect on the diaphragm will be destroyed and the spring will throw 10 the diaphragm outwardly to effect opening of the respective valve so that pressure can flow to the corresponding auxiliary cylinder and the motor throttle valve correspondingly adjusted. Such relief of the pockets is controlled 15 from the tracker board and the music sheet traveling thereover. As shown, pocket 40 connects through conductor 50 with tracker board passageway 51, while pocket 41 connects through conductor 52 with 20 tracker board passageway 53, the music sheet 2 having the slots 54 at desired locations to open to atmosphere at the proper time the respective valve controlling pocket so that the music sheet is automatically either accelerated 25 or retarded at the proper time. As shown pocket 41 is opened to atmosphere through one of the slots 54 while the music sheet still closes pocket 40 against atmosphere. Suction is effected in pocket 40 to hold the diaphragm in the valve 35 in closed position while diaphragm 43 has been released from suction effect and has been thrown outwardly to move the valve 36 to allow fluid under pressure to flow through 30 port 38 and conductor 32 to auxiliary cylinder 26. As a result of this, piston 24 in auxiliary cylinder 26 has been shifted inwardly and conductor 28 exposed so that the pressure is also admitted to the left of piston 13. Inward shifting of piston 24 having caused movement of valve block 15 toward the left to close the exhaust outlets 20 and 18 and to close the exhaust outlets 17 and 19 in advance of the piston 13. Upon such 45 movement of piston 13 throttle valve 11 is carried toward the left to close more of the passageway 10 so that the motor 4 and the music sheet 2 are retarded. If the tracker board passageway 51 were opened and passageway 53 closed then valve 35 would be opened and valve 36 closed and auxiliary cylinder 25 being connected with the pressure chest valve 15 would be shifted to the right and piston 13 shifted to move throttle 50 valve 15 to expose more of the passageway 10 so that the motor and music sheet would be accelerated. In this manner the tempo is automatically adjusted. The degree of acceleration and retardation is controlled by 55 the duration of exposure of the respective tracker board passageway to atmosphere, the distance of movement of piston 13 being controlled by the amount of fluid under pressure admitted to cylinder 14.

60 65 I thus provide throttle valve adjusting

mechanism actuated positively by fluid under pressure, the application of pressure being controlled automatically during passage of the music sheet over the tracker board. Adjustments can readily be made so that the tempo will be automatically regulated so that the rendition of a composition will be more in accordance with natural playing and will not sound mechanical.

I do not of course desire to be limited to the precise construction, arrangement and operation disclosed as changes and modifications can be made which would still come within the scope of the invention and

I claim the following:

1. In automatic regulator tempo mechanism, the combination of a main cylinder, a piston for said cylinder, a throttle valve connected with said piston, an auxiliary cylinder at each end of said main cylinder and a connection connecting each auxiliary cylinder with the respective end of the main cylinder, a piston valve in each auxiliary cylinder, a tracker board and a music sheet traveling thereover, a source of fluid pressure, means controlled by the passage of the music sheet over the tracker board for controlling the connection of either auxiliary cylinder with said pressure source, movement of a piston valve in response to fluid under pressure causing connection of the respective ends of the main cylinder to receive fluid under pressure from said auxiliary cylinder whereby the piston within said main cylinder is actuated, and a slide valve actuated in common by said piston valves to control the exhaust from the respective sides of said main cylinder piston.

2. In automatic tempo regulator mechanism, the combination with a tracker board, a music sheet and a motor for driving said music sheet over the tracker board, of a throttle valve for said motor, a main cylinder having a piston connected with said throttle valve, a source of pressure, valve mechanism for controlling the connection of said pressure source with either end of said main cylinder and to either side of said piston, a pneumatic compartment closed by a diaphragm at one side connected with each one of said valves, a source of suction connected with said compartments, said compartments being connected with respective openings in said tracker board, said suction being effective in said compartments upon closure of said tracker board passageways and being ineffective upon opening of such passageways, said diaphragms when influenced by suction being moved to close the respective valve, and means for shifting the diaphragms to open the valves when the suction effect thereon is removed.

3. In automatic tempo regulator mechanism, the combination of a main cylinder, a piston within said cylinder, a throttle valve

connected with said piston, an auxiliary cylinder at each end of said main cylinder and having connection therewith, a piston in each of said auxiliary cylinders, exhaust valve mechanism for said main cylinder controlled by said auxiliary cylinders and pistons, a tracker board and music sheet, and means controlled by the passage of the music sheet over the tracker board for controlling application of fluid to said cylinders for operating said main cylinder piston and thereby said throttle valve.

4. In automatic tempo regulator mechanism, the combination of a main cylinder, a piston in said cylinder, a throttle valve connected with said piston, an auxiliary cylinder at each end of said main cylinder and each auxiliary cylinder having a piston, relief valve mechanism for said main cylinder controlled by said auxiliary cylinder pistons, a source of fluid pressure, a tracker board and music sheet, pneumatic means controlled by the passage of the music sheet over the tracker board for controlling the connection of either auxiliary cylinder with said fluid pressure source, and a fluid connection from each auxiliary cylinder to the main cylinder exposed by the respective auxiliary cylinder pistons to receive fluid under pressure from said auxiliary cylinder.

5. In automatic tempo regulator mechanism, the combination of a main cylinder, a piston for said cylinder, a throttle valve connected with said piston, an auxiliary cylinder at each end of said main cylinder and each having a piston, relief valve mechanism for said main cylinder controlled by

said auxiliary cylinder pistons, a source of fluid pressure, a tracker board and music sheet traveling thereover, pneumatic means controlled by the passage of the music sheet over the tracker board for controlling the connection of said fluid pressure source with either auxiliary cylinder, admission of fluid under pressure to either auxiliary cylinder causing movement of the piston therein and shifting of the relief valve mechanism for the main cylinder, and means controlled by such movement of the auxiliary cylinder pistons for connecting the main cylinder with said fluid pressure source whereby said main cylinder piston is actuated and said throttle valve adjusted.

6. In automatic regulator mechanism, the combination of a main cylinder, a piston within said cylinder, an auxiliary cylinder at each end of said main cylinder and having connection therewith, a piston in each of said auxiliary cylinders, exhaust valve mechanism for said main cylinder controlled by said auxiliary cylinders and pistons, a tracker board and music sheet, and means controlled by the passage of the music sheet over the tracker board for controlling application of fluid to said cylinders for operating said main cylinder piston.

In witness whereof, I hereunto subscribe my name this 28th day of August, A. D., 1912.

PAUL B. OLSON.
